UNITED STATES PATENT OFFICE.

JOHN ASHLAND WHERRY, OF NEW ORLEANS, LOUISIANA.

COLLATED WORK SHEET.

Application filed June 14, 1922. Serial No. 568,192.

To all whom it may concern:

Be it known that I, JOHN A. WHERRY, a citizen of the United States, residing at 5911 Prytania Street, in the city of New Orleans, State of Louisiana, have invented certain new and useful Improvements in Collated Work Sheets; and I do hereby declare the following to be a full, clear, and exact description of the invention, such as will enable others skilled in the art to which it appertains to make and use the same.

The invention relates to collated work sheets and has for its object to provide a simple and effective arrangement of a main work sheet, such as a ledger sheet, and a secondary work sheet, such as a statement, which latter is made in the form of a continuous band extending around the main work sheet and engaging a slot in a transverse edge of the main sheet to lock the sheets together. The sheets thus associated preferably having a sheet of carbon paper or other transfer medium interposed between them, which carbon sheet is also preferably in the form of a continuous band, the main sheet having a column of figures along one edge corresponding to line spaces of a typewriting machine in which the collated sheets are employed, the front face of the supplementary sheet having a similar column of figures along one edge, and the rear portion of the band-like supplementary sheet having a series of lines of perforations similarly spaced, to correspond with the line spacing of a typewriter, said perforated lines preferably being provided with two columns of figures in reverse order to each other, the co-ordinated sheets providing a means for a permanent record on both sides of the main sheet, and the supplementary sheet affording means for making a removable record for a given period of time, which record may be included on both the front and back sections of the band-like supplementary sheet.

The invention is illustrated in the accompanying drawings, in which,

Fig. 1 is a front elevation of the main and supplementary sheets in assembled relation;

Fig. 2 is a rear elevation of the same;

Fig. 3 is a sectional elevation of the assembled sheets.

Referring to the drawings, 1 represents the main record sheet, which, for the purpose of illustration, is an ordinary ledger sheet which may be in the form of a card, or leaf such as employed in a loose-leaf book, said sheet being provided with the usual concomitants of a ledger record including a space for the heading, and the usual column indicia such as Date, Items, Debits, Credits and Balance, and if desired, additional columnar spaces for additional data. One or both of the transverse edges of the sheet 1 is provided with a slot or indentation, as represented by the numerals 2 and 3, of a width substantially equal to that of the supplementary sheet. Near one marginal side edge of the sheet 1 there is provided a series of consecutively numbered spaces corresponding to the line spacing on the typewriting machine with which the assembled sheets are employed.

The supplementary sheet 10 is formed as a continuous band or belt-like strip which extends longitudinally of and overlies the front and rear faces of the main sheet 1, and engages the slot or slots 2, 3, in the main sheet, thereby locking the two sheets together and preventing any lateral, or longitudinal movement of the supplementary sheet with respect to the main sheet. The front face of the supplementary sheet is provided with similar headings, spaces, columns and rulings as the portion of the main sheet which underlies the former, such for example, as the heading space for the data of the account, the indicia caption spaces corresponding to the similar spaces on the main sheet, and along one marginal edge there is disposed a column 12 of consecutive numbers corresponding to the numeral column 5 on the main sheet. The rear section of the continuous band-like supplementary sheet is provided with a series of transverse linear perforations 13, which include the entire rear section and the lines of the folds or creases where the supplementary sheet passes over and around the bottoms of the slots in the edges of the main sheet, and preferably these perforated lines

are provided with rows or columns of consecutive numbers, the numbers in the respective columns being in reverse order, and the lines being spaced to agree with the typewriter line spacing.

When the main and supplementary sheets have been assembled as indicated, the front and back sections of the supplementary sheet closely overlie the adjacent faces of the main sheet and it will be apparent that a continuous record printed by the typewriting machine on the supplementary sheet will be transferred to the main sheet. Any suitable means for effecting the transfer may be employed, such, for example, as providing the inner faces of the secondary sheet with a transferring composition, but the transfer is preferably effected by interposing a carbon transfer sheet 20 between the main and supplementary sheets. If desired, the carbon sheet may also be formed as a continuous band, in which event only one section of the carbon sheet corresponding in length to the main sheet will be coated with the transfer composition, in order to prevent the record as printed by the typewriter being impressed on the back of the main sheet. The advantage of forming and applying the carbon transfer sheet as a continuous band is that it may be accurately adjusted with the supplementary sheet so as to be always in proper relation to transfer the record to the primary sheet. Obviously also, the transfer sheet may consist of a single sheet 35 of carbon paper and the like, of the same length as the main sheet, which may be slipped in between the supplementary and main sheets and removed after one side of the record sheets have been printed, and 40 afterwards inserted between the rear section of the supplementary sheet and the back face of the main sheet.

The mode of assembling and using the collated sheets as above described will be apparent from the foregoing description, but a specific exemplification of the use of the invention in collating ledger sheets and statements, as illustrated in the drawing, will render the advantages of the invention 50 perfectly clear. Assuming that the statement is to represent transactions covering a month, and the ledger account has been started on a new sheet, the supplementary sheet is slipped over the main sheet by bending the latter slightly in a direction from top to bottom, and the numeral 1 of column 12 on the supplementary sheet brought into alignment with numeral 1 of column 5 of the main sheet. If a separate transfer sheet 55 is employed, the same is applied simultaneously with the supplementary sheet. The two sheets are maintained in the assembled relation indicated during the entire period covered by the statement or supplementary sheet, and the successive items are written

on the latter and simultaneously transferred to the main sheet. Should the number of items of transactions exceed the number of lines on the front face of the ledger sheet, it is necessary only to reverse the latter and begin the writing of the items on the next line on the reverse side counting from the bottom of the main sheet, which will make the record on the secondary sheet continuous, and in proper successive order. 70 After the record for the complete period represented by the statement or supplementary sheet has been finished, the supplementary sheet is removed by tearing along any one of the perforated lines on the rear section thereof, after which a new supplementary sheet may be substituted therefor. If the data to be recorded on the supplementary sheet represents a continuation of the data already recorded on the main sheet, as for 80 example, when the main sheet contains a record of transactions covering a month, and including the first ten lines represented by column 5, the new supplementary sheet will be so applied to the main sheet that the numeral 1 in column 12 will come opposite numeral 11 in column 5, and the data recorded on the supplementary sheet will represent the transactions during the period covered by the statement or supplementary sheet, and the data thus recorded will constitute a continuation of the entire account on the main sheet. After the record on the supplementary sheet has been completed, and the latter disengaged from the main sheet, the extra length or unused portion of the supplementary sheet may be removed by tearing the same at any one of the perforated lines 13, as 90 will be understood.

What I claim is:

1. The combination of a main work sheet having a slot in a transverse edge thereof, a continuous supplementary work sheet extending longitudinally of and around the main sheet and engaging said slot, and a transfer sheet interposed between the main and supplementary sheets.

2. The combination of a main work sheet having a slot in a transverse edge thereof, a continuous supplementary work sheet extending longitudinally of and around the main sheet and engaging said slot, and an endless transfer sheet interposed between the main and supplementary sheets.

3. The combination of a main work sheet having a slot in a transverse edge thereof and a column of figures indicating line spaces along one side, and a continuous band supplementary work sheet extending longitudinally of and around the main sheet and engaging said slot said supplementary sheet having a column of figures on one edge of the front section corresponding to the column of figures on the main sheet.

4. The combination of a main work sheet

having a slot in a transverse edge thereof and a column of figures indicating line spaces along one side, and a continuous band supplementary work sheet extending longitudinally of and around the main sheet and engaging said slot, said supplementary sheet having a column of figures on one edge of

the front section corresponding to the column of figures on the main sheet, and a series of transverse linear perforations correspondingly spaced on its rear section. 10

In testimony whereof I affix my signature.

JOHN ASHLAND WHERRY.
